KNIFE

Earl C. Barr, P.O. Box 445, Waxahachie, Tex.

Filed Mar. 23, 1960, Ser. No. 59,841

Term of patent 14 years

(Cl. D22—3)

Fig. 1

Fig. 2

Fig. 3

Fig. 4

I claim:

The ornamental design for a knife, substantially as shown.
